(57) **CLAIM**

The ornamental design for a tire as shown and described.

DESCRIPTION

FIG. 1 is a front elevation view of the tire showing my new design;

FIG. 2 is a front perspective view thereof;

FIG. 3 is an enlarged partial top elevation view thereof;

FIG. 4 is a top elevation view thereof;

FIG. 5 is a left side elevation view thereof; and,

FIG. 6 is a right side elevation view thereof.

The broken lines shown in FIG. 4 show the portion of the tire from which the enlarged partial view of FIG. 3 is taken and forms no part of the claimed design.
